(57) **CLAIM**

The ornamental design for a stamp for cementitious material or the like, as shown and described.

DESCRIPTION

FIG. 1 is a top plan view of a stamp for cementitious material or the like showing my new design;

FIG. 2 is a side elevation thereof; and,

FIG. 3 is a top perspective view thereof.

The phantom lines shown do not form a part of the claimed design.

1 Claim, 2 Drawing Sheets

FIG. 1

FIG. 2

FIG. 3
